ASSIGNORS TO RITE-CONLEY MANUFACTURING COMPANY, OF PITTSBURGH, PENN-
SYLVANIA, A CORPORATION OF NEW JERSEY.

MEANS FOR CONTROLLING THE OPERATION OF GAS-RETORTS.

1,144,169.

Specification of Letters Patent. Patented June 22, 1915.

Application filed August 22, 1914. Serial No. 858,072.

To all whom it may concern:

Be it known that we, HENRY A. CARPENTER and ARTHUR W. WARNER, citizens of the United States, residing at Sewickley, in the county of Allegheny and State of Pennsylvania, have invented certain new and useful Improvements in Means for Controlling the Operation of Gas-Retorts, of which the following is a specification.

10 The charging and discharging of gas making retorts necessitate properly placing the mechanisms which are involved in such operations. This is true of the discharge end of the retort as well as its inlet end, 15 particularly if the discharge is into a producer charging machine, it being necessary to have the latter in receiving position before the scoop or other tool is entered in the retort. A premature operation endangers the mechanism and is liable to result in injury to the producer charger operator.

20 The primary object of the present invention is to insure the proper positioning of the producer charger or other coke receiving means before the retort tool can be operated. In the present embodiment, this is accomplished by providing a controlling circuit for the tool actuating motor, with an interruption therein which is closed by the producer charging machine only when in alignment with the retort and in proper position to receive the coke discharged therefrom. This controlling circuit may also be provided with other interruptions for auxiliary 35 controlling devices, one of which may be closed by the retort charging machine when the tool is in alignment with the retort to be operated upon, and other interruptions 40 may be controlled by the retort doors. While these auxiliary controlling devices may be used in conjunction with the control effected by the producer charger or other coke receiving means, it will be understood that 45 the latter may be used alone and without regard to such auxiliary devices.

It is a further characteristic of the present invention that the manual control for the apparatus is mounted on the retort 50 charging machine, which however, is operative only when the controlling circuit has been closed as a result of properly positioning the producer charger, and only after the auxiliary controlling devices have been

placed in tool operating position if such devices are employed.

In the accompanying drawing, Figure 1 is a diagrammatic illustration of a form of apparatus embodying the invention. Fig. 2 is a detail of the circuit closing means associated with one of the retort-doors.

Referring to the drawings, 2 designates a bench and 3 one of a series of retorts therein.

4 designates the frame of a retort charging machine which is movable along the front of the bench on track 5. Mounted in any suitable manner on the traveling charging machine is a carriage 6 for a charging and discharging scoop or other retort tool 7. Carriage 6 may be actuated on track 8 by a threaded shaft 9 which extends through a nut or head 10 of the carriage, shaft 9 being geared at 11 to an electric motor 12. Also geared at 13 to shaft 9 is a screw shaft 14, the rotation of which slides the contact bar 15 relatively to certain circuit terminals, as will be presently explained. Any suitable means, as an electric motor 16, may be utilized for moving the retort charging machine on track 5.

At the opposite side of the bench, 17 indicates gas producers surmounted by track 18 on which moves the producer charging machine which may include the laterally movable transfer receptacle 20.

The apparatus preferably embodies a three-phase electric system having three conductors A, B and C, for the retort charging machines which, respectively, are engaged by the trolleys a, b and c.

D and E are conductors for the tool motor controlling circuit, hereinafter described, and engaging the same are trolleys d and e, respectively.

A double or reversing solenoid switch 25 directs the current to the tool actuating motor 12, the "forward" movement being controlled by solenoid 26 and the "backward" movement by solenoid 27. This double solenoid switch is of usual and well known construction. Mounted in any suitable manner on the retort charging machine is the manually operated controller Z which may be moved to place its circuit closing arm Z' in two positions, one for effecting the retort entering movement of the tool 7 and the other for retracting the tool.

The wiring for motor 12 and switch 25 is

as follows:—Wire 28 from trolley *a* leads to switch 25; wire 29 from trolley *b* to switch 25; wire 30 from trolley *c* to motor 12. Tracing the circuit for "forward" solenoid 26, the upper terminal thereof is connected by wire 29 to trolley *b*, and wire 31 from the other end of the solenoid extends to trolley *d* and conductor D to the rear and front of bench 2, then to conductor E, 10 trolley *e*, and to contact arm 37 of the sliding switch, with an interruption 35 at controller Z. From contact arm 37 the circuit is continued through sliding contact bar 15 to contact arm 38 and through wire 31' to wire 30 which connects with trolley *c*.

The circuit for the "backward" or reversing solenoid 27 is as follows: One end of this solenoid is connected by wire 29 leading to trolley *b*. The other end of the solenoid is connected by wire 56 to contact arm 57 of the sliding switch; with an interruption 35' at controller Z. With bar 15 in engagement with contact arm 57, as it is when the bar is depressed and the tool entered in the retort, the "backward" circuit is through the contact bar, contact arm 38, and branch wire 31' to wire 30 and trolley *c*.

The portion of the controlling circuit 31 which extends to the bench is provided primarily with an interruption 60 which is adapted to be bridged by the circuit closing device 61 on the producer charger transfer receptacle 20 when the latter has been properly positioned beneath a retort for receiving the coke discharged therefrom. Thus, it will be seen that unless the retort charging machine is in proper position the "forward" solenoid 26 cannot be operated even though the manual controller Z is moved to bridge circuit interruption 35. It is characteristic of a preferred adaptation of the invention to locate controller Z on the retort charging machine and to have the same operate in conjunction with the circuit closer carried by the producer charger, so that the operator cannot cause the tool to enter the retort until after the producer charger has been properly positioned.

Circuit 31 may if desired have additional interruptions at the bench, such as interruption 62 for the rear door of the retort, interruption 63 for the front door of the retort, and interruption 64 for the retort charging machine, a circuit closing device 65 being adapted to bridge interruption 64 when said machine is in position to align tool 7 with the retort. The door 66, Fig. 2, may be the door for either the inlet or the discharge end of the retort, with an arm 67 projecting therefrom which is adapted to bridge interruption 62 or interruption 63, when the doors are open, thereby making it impossible for a "forward" movement of the tool to ensue until both the front and rear doors have been opened. And with interruption

64 such operation cannot take place until the tool is in alignment with the carriage. While the several auxiliary controlling means, embodying interruptions 62, 63 and 64 may be used severally or collectively in connection with interruption 60, it will be understood that the latter may be employed in the absence of any or all of such auxiliary controls, in which case the interruptions for the auxiliary controls would be simply omitted, as will be understood.

The contact arms 37, 38 and 57 are so arranged that as traveling bar 15 approaches the outer limit of its movement, as in Fig. 1, it leaves arm 57, thereby opening the "backward" circuit and bringing the tool to a standstill in withdrawn position. As bar 15 approaches the inward limit of its travel, it coasts off of arm 37, thereby opening the "forward" circuit and stopping the tool, but leaving bar 15 in engagement with contact arms 38 and 57 in readiness for the "backward" traverse of the tool when controller Z is thrown to close interruption 35'.

Those features of the apparatus herein disclosed relating to control of the retort tool or other retort manipulating means by the position relatively to the retort of movable retort co-operating mechanism, are broadly claimed in applicants' copending application, Serial No. 855,412, filed August 6, 1914.

What we claim is:—

1. The combination of a retort, mechanism movable relatively to the discharge end of the retort and having predetermined position when the retort is discharging, a retort discharging tool and a tool motor, a tool controlling circuit having an interruption, and a circuit closing device actuated by said movable mechanism and adapted to close said interruption when said mechanism is in predetermined position.

2. The combination of a retort, a receptacle movable to and from position for receiving the retort discharge, a retort discharging tool and tool motor, a tool controlling circuit having an interruption, and a circuit closing device movable with said receptacle and adapted to close said interruption when the receptacle is in position to receive the retort discharge.

3. The combination of a retort, a retort discharging tool and a tool motor, a tool controlling circuit having an interruption, a gas producer, a producer charging machine movable to and from position for receiving the retort discharge, and a circuit closing device movable with said machine and adapted to close said interruption when the machine is in position to receive the retort discharge.

4. The combination of a retort, retort co-operating machines movable relatively to opposite ends of the retort, a retort dis-

- charging tool mounted on the machine at the front of the retort and a tool motor, a tool controlling circuit having interruptions at opposite ends of the retort, and circuit closing devices carried by said machines and adapted to close said circuit interruptions when said machines, respectively, are in predetermined position relatively to the retort.
- 10 5. The combination of a retort, a retort closure, a producer charging machine movable relatively to the retort and into which the retort is adapted to discharge, a retort discharging tool and a tool motor, a motor controlling circuit having two interruptions, a circuit closing device carried by the producer charger and adapted to close one of said interruptions when the charger is in position to receive the retort discharge, and 20 a circuit closing device actuated by the retort closure when the latter is open to close the other circuit interruption.
6. The combination of a retort, a retort charging machine and a producer charger movable, respectively, relatively to the inlet and discharge ends of the retort, a retort tool mounted on the retort charging machine, a tool motor, a tool controlling circuit having an interruption, a circuit closing device actuated by the producer charger to close said interruptions, and a controller 25 for said circuit mounted on the retort charging machine.
7. The combination of a retort, a retort charging machine and a producer charger 35 movable, respectively, relatively to the inlet and discharge ends of the retort, a retort tool mounted on the retort charging machine, a tool motor, a tool controlling circuit having interruptions at opposite ends of the 40 retort, circuit closing devices actuated, respectively, by the producer charger and retort charging machine for closing said interruptions, and a controller for said circuit mounted on the retort charging machine. 45
8. The combination of a retort, coke receiving mechanism movable relatively to the retort and having predetermined position when the retort is discharging, retort discharging means, and means made operative by the coke receiving mechanism when in position to receive coke from the retort for making operative the retort discharging means. 50
